(57) **CLAIM**

The ornamental design for an earphone, as shown and described.

DESCRIPTION

FIG. 1 is a top, front, left side perspective view of an earphone, showing my design.

FIG. 2 is a bottom, rear, right side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a perspective view of the earphone in an earphone box.

The details shown in broken lines form no part of the claimed design.

The broken lines depict environment that is for illustrative purposes only, the broken lines form no part of the claimed design.

1 Claim, 9 Drawing Sheets(56)
